UNITED STATES PATENT OFFICE.

JOHN W. GATES, OF MONTREAL, QUEBEC, CANADA.

FURNACE CONSTRUCTION.

1,341,896.

Specification of Letters Patent. Patented June 1, 1920.

Application filed February 12, 1918. Serial No. 216,795.

To all whom it may concern:

Be it known that I, JOHN W. GATES, a subject of the King of Great Britain, and resident of the city of Montreal, in the 5 Province of Quebec and Dominion of Canada, have invented certain new and useful Improvements in Furnace Construction, of which the following is a full, clear, and exact description.

10 This invention relates to improvements in boiler and other furnaces, and the object of the invention is to provide a simple and inexpensive composite lining block, the burned out portion of which may be very readily 15 replaced and also to provide facilities for holding the block facing in place and for its removal.

A further object is to provide a lining block, which may be replaced without disturbing the brickwork of the furnace.

20 A still further object is to provide a lining block which will be positively held against moving bodily or tipping into the furnace and which is so constructed that accumulations of grit fallen from the casing 25 are excluded from the base of the block, so that the block is not forced into the furnace.

Another object is to provide a furnace 30 block which will reduce the number of seams in a furnace, thus reducing the liability of short circuiting and consequent loss of heat to a minimum.

At the present time, furnaces are ordinarily provided with linings of refractory material, such as fire brick, extending from the level of the grates upwardly for a suitable distance. These linings burn out in a short time and require to be renewed. For 35 this reason, it is impossible when using ordinary refractory bricks to properly key the same into the wall, with the result that a straight seam extends for a considerable distance vertically all around the furnace. Expansion and contraction of the brickwork is 40 accompanied by a constant fall of grit, which works down through this seam and accumulates at the bottom thereof, gradually forcing the lining bricks into the furnace, so that the lining burns out more 45 rapidly or else collapses. If, in order to prevent the occurrence as above outlined, the lining bricks are keyed into the wall, it becomes necessary to disturb a large part of 50 the furnace wall to renew the lining. In 55 the furnace wall to renew the lining. In Patent No. 1,300,874, I have disclosed a

stepped lining block which overcomes the difficulties above enumerated but it has the disadvantage that the rear portion of the block, which is perfectly sound and serviceable, must be discarded when it becomes necessary to renew the block, owing to the face being burned away.

According to the present invention, this disadvantage is overcome by providing a composite block having a rear portion, and a renewable face portion securely locked to the rear portion. When in position, the two parts of each block are securely locked together, so that the block is for all practical purposes a unit having a wide base and a stepped rear face, which meshes with the brickwork of the casing to hold the block against tipping into the furnace and to prevent accumulations of grit at the base of the block, which would force the block bodily into the furnace.

The device consists essentially of a block having a rear portion of suitable shape, designed to be fitted into a suitable recess in the brickwork of a furnace casing and having a transverse groove on the front face thereof. A facing is provided for the block having a transverse rib which hooks into the groove and securely holds the facing in position. A stretcher course of ordinary brick or firebrick is provided between the facing and the furnace wall proper, to hold the facing against movement necessary to unhook and disengage it.

In the drawings which illustrate the invention:—

Figure 1 is a fragmentary cross sectional view of a furnace wall showing an elementary form of furnace lining block according to this invention in end elevation.

Figs. 2 to 12 inclusive are end elevations showing various modifications which fall within the scope of this invention.

Fig. 13 is a fragmentary plan view showing the lapping of the facing blocks of any of the preceding figures.

Referring more particularly to the drawings, 21 designates the wall of a furnace casing which is provided from about the level of the grate bars 22 upward with a recess 23 preferably, having a stepped rear upper surface 24 formed by a cornice 25, which supports the wall above the recess. This cornice is preferably formed of binder 105 courses 26 for the depth of the block and, above that, a single stretcher course 27 and

- a binder course 28; the ends of the bricks in the latter course projecting flush with the wall above the recess.
- The lining consists of a series of blocks 5 each composed of a backing 29 and a facing 30. Each lining block may be stepped on the rear face to mesh with the cornice and thus provided with a series of ledges 31 or may be without steps as in Figs. 11 and 12.
- 10 Preferably the division between the backing and facing occurs in the vertical plane of the front edge of the upper ledge 31, as clearly shown, thus forming of the backing a stepped block in itself but may be arranged otherwise, for example as shown in 15 Figs. 9 and 10. The front face of the backing may be provided with one or more transverse grooves 32. The rear surface of the facing may be provided with an equal 20 number of transverse ribs 33 adapted to engage in the groove or grooves of the backing to hold the facing to the backing and against tipping or horizontal movement into the furnace. In order to insure the desired 25 locking, the groove extends below the lip 34 defining it at the front surface of the backing, so that the rib 33, which depends below the line at which it springs from the facing, will hook over the lip. The front surface 35 of the facing may be inclined from bottom to top toward the rear. In inserting lining blocks of this character in a furnace wall, the backing and facing may be put together, or separately. When the facing is 35 in place, there will be a space 36 between the facing and the wall, in which a stretcher course 37 of refractory or of ordinary brick is loosely laid. This stretcher course 37, which is not at all under load, serves merely 40 as a filler to hold the facing 30 against the movement necessary to unhook it from the backing. When the facing becomes burned out, all that is necessary is to remove the stretcher course 37 and pry the facing 30 45 upwardly out of engagement with the backing. New blocks can then be very quickly inserted and the stretcher course 37 replaced, using new bricks if necessary.
- As will be readily seen, the difference between the blocks shown in Figs. 1 and 2 is 50 that in the latter figure, two grooves and ribs are provided, instead of a single groove and rib shown in the former figure. Figs. 3 and 4 show the single and double rib 55 arrangement on the facing block combined with a rearward sloping portion 38 on the facing, which increases the depth of the base 39 of the facing, so that a greater thickness of material is provided where the greatest 60 burning out or wastage occurs and the facing thus rendered serviceable for a longer period before being burnt out. In Figs. 5 and 6, the base features of the first and second groups of figures are combined with a 65 slight variation in the arrangement of

grooves and ribs, this arrangement residing merely in a reversal so that the backing is provided with a rib 40 and the facing with a groove 41. In Figs. 7 and 8, another reversal of the arrangement is shown which 70 resides in reversing the direction of the hooking-on ribs, so that the facing is held in its locking relation from below instead of from above. In Figs. 9 to 12 inclusive, lining blocks are shown which are the same as 75 in the preceding figures in so far as the connection of the backings and facings is concerned, and which show that the facing may be applied to blocks of different shapes. It will be noted that in Figs. 11 and 12, the 80 backing and facing blocks are exactly alike. In Fig. 13, the method of lapping the blocks to prevent leakage of heat through the vertical seams between them is illustrated. Each facing block is provided at one end 85 with a rabbet 42 and at the opposite end with a lip 43 adapted to occupy the rabbet of the adjoining block. The precise method of sealing the vertical joints between the blocks is obviously not limited to the method 90 disclosed in this figure.

From the foregoing description, it will be seen that the invention resides broadly in two features, the first of which is the provision of a lining block made in two parts, the outer or facing part being readily removable without disturbing the inner or backing part said block preferably having steps or ledges thereon to prevent accumulations of grit at the base of the block, which would 100 force the block bodily into the furnace, said ledges also engaging under the casing and holding the block against tipping into the furnace.

The second feature is the provision of a 105 stretcher course of brick in the furnace wall to hold the block facings against unhooking, which stretcher course may be readily removed without danger to the wall to liberate the facings for renewal.

Having thus described my invention, what I claim is:—

1. In furnace construction, the combination with a furnace wall of a lining block having a stepped rear face forming at the 115 base a rearward extension engageable with a furnace wall to hold the block against tipping into the furnace, and forming intermediate the base and top a rearwardly extending ledge adapted to exclude fallen grit from the base of the block, said block comprising a backing and a removable facing, and a brick course in the wall removable to form a space into which the facing may be shifted for removal.

2. In furnace construction the combination with a furnace wall of a stepped shape lining block providing at the base a rearward extension engaging the wall and held thereby against tipping, said block compris- 130

- ing a backing and a facing hooked onto the said backing, and a course of bricks in the wall holding the facing against unhooking.
3. In furnace construction, the combination with a furnace wall having a recess from the level of the grates upward, the wall above said recess being self supporting, of a composite lining block in said recess, comprising interlocking backing and facing portions separable by relative vertical movement, and a filling course in said recess holding the parts of the composite block against relative vertical movement.
4. In furnace construction, a wall having a recess extending from the level of the grate upward, the wall being self-supporting above the recess, and blocks in said recess each comprising a backing and a protective facing, said facings being formed for interengagement with the facings of adjoining blocks to close the seams between the blocks to the escape of heat, and means for removably holding the facings in place.
5. In furnace construction, a wall having a recess from the level of the grate upward, a block in said recess having rearwardly extending ledges engaging the rear surface of the wall recess and holding the block against tipping into the furnace, a protective facing releasably connected to the block, and a filling in the recess holding the facing against disconnection from the block.
6. In furnace construction, a wall having a recess from the level of the grate upward, and a block in said recess comprising a backing and a separable facing having interengaging hooked ledges formed to permit relative movement of the block parts in an inclined plane, and removable means in said recess holding the facing against movement in an inclined plane.
7. In furnace construction, a wall having a recess from the level of the grate upward, a block in said recess comprising a backing and a separable facing, said backing and facing including interengaging hooked ledges holding the facing, said ledges being disengageable by vertical movement of the facing, and a row of bricks in the wall recess holding the facing against vertical movement necessary to disengagement of the ledges.
8. In furnace construction, the combination with a furnace wall having a recess from approximately the level of the grates upward, the wall above the recess being self-sustaining, of a removable block in the inner portion of said recess and a removable facing in the outer portion of the recess releasably connected to the block, said block and facing being removable without disturbance of the wall.
9. In combination with a device according to claim 8, a removable block in the outer part of said recess holding the facing in connected relation with the block.
10. In furnace construction, a wall having a recess from the level of the grate upward adapted to removably receive lining blocks, lining blocks in said recess comprising separable backing and facing portions, and means holding the backing and facing portions against separation in the wall recess.
11. In furnace construction, a wall having a recess from the level of the grate upward adapted to removably receive lining blocks, lining blocks in said recess comprising separable backing and facing portions, and means coöperating with the wall to hold the backing and facing against separation in the wall recess.

In witness whereof I have hereunto set my hand.

JOHN W. GATES.
